WILLIAM E. RICHARDS, OF TOLEDO, OHIO.

TROLLEY-LINE SUPPORT.

1,373,972.

Specification of Letters Patent.

Patented Apr. 5, 1921.

Application filed February 7, 1920. Serial No. 357,061.

To all whom it may concern:

Be it known that I, WILLIAM E. RICHARDS, a citizen of the United States of America, residing at Toledo, Lucas county, Ohio, have 5 invented new and useful Trolley-Line Supports, of which the following is a specification.

This invention relates to line take-up means between relatively movable sustaining 10 points.

This invention has utility when incorporated in overhead trolley systems for lift bridges.

Referring to the drawings:-

15 Figure 1 is a diagrammatic view in side elevation of an embodiment of the invention in a bascule type of rolling lift bridge;

Fig. 2 is an end elevation of the free end of the bridge lift of Fig. 1;

20 Fig. 3 is a fragmentary detail view of the automatic slack take-up trolley pole mounting;

Fig. 4 is a detail view of trolley connection to one of the poles; and

25 Fig. 5 is a section on the line V—V Fig. 4.

Bridge approach or way 1 extending to pier 2 has adjacent bridge lift 3 and on the approach a fixed trolley pole 4 to which extends from the landward side a trolley wire 30 or line 5 herein shown as a solid copper wire usual in street railway work. Over this lift 3 extend rails 6 of electric street railway so that cars may travel, with trolleys from the car extending to overhead trolley wire.

35 Lift bridges of the fixed pivot type as well as the rolling lift type in upward movement of the free end would tend to permit a grounding or dragging of a trolley line against the floor of the bridge as the lift 40 ascended. Such action, if in the nature of a ground, would be disastrous to the service while furthermore it is a rubbing or abrading of the wire which is objectionable in street railway trolley service.

45 Herein applicant has, by the expedient of the invention herein set forth, overcome such difficulties automatically in an efficient manner with reliable details of construction holding up in the arduous service regardless 50 of weather or operation conditions. To this end near the extreme or lift end portion of the lift 3 there is provided a pair of bearings 7 for trunnions 8 fixed with collar 9 on line pole 10. Below the deck of the bridge lift 55 3 this pole 10 has counterweight 11 swing-

able against stop 12 when the pole 10 is vertical. This precludes any swinging of the pole 10 toward the pole 4 so that when the lift 3 is down there may be no slack in the line or trolley wire between poles 4 and 10. The rocking of this pole 10 is limited to one direction away from the stop 12 in order that this pole 10 may approximate vertical position when the lift 3 is inclined.

As a shield for traffic conditions as well as 65 possible disturbance from weather there is provided a housing or hood 13 carried by the pole 10 above the collar 9 which hood 13 works under hood 14 fast with the lift bridge 3, this latter hood 14 having a slot 15 70 permitting swing of the pole 10.

In the double track railway system as herein disclosed, it is convenient to have pole 10 disposed between the two tracks 6 and to carry cross arm 16 sustaining pan 17. 75 This pan 17 has a medial rib 18 serving to guide the trolley wheel for passing hinge joint 19 connecting trolley wire 20 respectively to the poles 4 and 10. The length of the lift span 3 may govern the number and 80 disposal of the poles thereon.

The principle as herein disclosed is that simultaneously with the operation of the lift the counterweight or means may be effective for rocking a pole relatively to the bridge 85 for changing the distance between the line engaging portions of the poles, thereby reducing the slack between said poles to an extent that the trolley wire may not swing to ground in the normal operation of the 90 bridge.

As herein disclosed this is effected with solid trolley wire 20 as the hinged connected flexible member between the two relatively movable poles 4 and 10. This provides a 95 substantial structure which in continued operation even in most adverse weather conditions is reliable in responding to bridge operation and traffic conditions.

What is claimed and it is desired to secure 100 by United States Letters Patent is:-

1. An overhead line, relatively movable supports for maintaining said line in normal line position and during the full range of travel from normal position, one of said 105 supports in its movement having means reducing the distance between the line engaging portions of said supports.

2. An overhead trolley line, a fixed support, a relatively movable support, and 110

means for swinging the top of the movable support away from the fixed support during travel of the movable support.

3. A bridge approach, a lift bridge, to which the approach extends, an electric railway track thereover, a trolley line, a trolley pole at the bridge approach, and a trolley pole on the bridge lift, said line being directly connected to said poles, one of said poles being rockable during lifting of the bridge to reduce the slack in the line between said poles.

4. A bridge lift, a trolley line, a trolley support clear of the bridge lift, a trolley support near the free end of the bridge lift, and hinged connection between said supports and the line.

5. A lift bridge trolley support including a counterweighted tiltable pole.

6. A lift bridge trolley support including a pole having trunnion bearing means, a counterweight below said means, and trolley engaging means above said bearing means.

7. A lift bridge trolley support including a counterweighted tiltable pole, and stop means precluding tilt of the pole in one direction.

8. A lift bridge trolley support including a tiltable pole, a trolley line sagging from the supporting pole in bridge lifting, and a hinge connection between the line and pole.

9. A lift bridge trolley support including a member swingable as to the bridge in bridge movement, a trolley line, and a hinge connection between the line and member.

In witness whereof I affix my signature.

WILLIAM E. RICHARDS.
